UNITED STATES PATENT OFFICE.

JAMES M. AULT, OF DECATUR, INDIANA.

BUILDING-BLOCK.

979,913.

Specification of Letters Patent. Patented Dec. 27, 1910.

Application filed January 19, 1907. Serial No. 353,122.

To all whom it may concern:

Be it known that I, JAMES M. AULT, a citizen of the United States, residing at Decatur, in the county of Adams and State 5 of Indiana, have invented certain new and useful Improvements in Building-Blocks, of which the following is a specification.

My invention relates to an improvement in building blocks, preferably made of cement, 10 or other plastic material, and the object is to provide a block which will prevent rain or snow from forcing through and making the inside wall damp.

Another object of my invention is to do 15 away with the half or mitered blocks, and I have provided means whereby the blocks at the corners can be connected together, and at the same time make a tight connection.

My invention relates to certain other novel 20 features of construction and combinations of parts which will be hereinafter described and pointed out in the claim.

In the accompanying drawings Figure 1 is a view of a portion of a wall. Fig. 2 is 25 a bottom view. Fig. 3 is a perspective view of one of the corner blocks. Fig. 4 is a view of another corner block. Fig. 5 is a bottom view of one of the corner blocks.

A, represents the block, and B, B, are 30 vertical openings or apertures through the block. The block has a raised tongue 1 on the upper edge, and on the lower edge it is provided with a groove 2, which is adapted to receive the tongue 1, of the block upon 35 which it is placed.

The ends of the blocks are provided with a tenon 3, and a mortise 4, which tenons are received in the mortise of the adjoining 40 block. In this way, a tight connection is made, and which adds strength to the wall, and prevents air and water from sifting through any cracks which might be formed by the ordinary block.

In the corner blocks, I have a projection 45 5 or recess 6 formed on one side, which are adapted to interlock with either the mortise 4 or tenon 3, and in this way do away with the half or miter blocks.

On the corner blocks, or all the blocks 50 might be made in the same manner, I have

cut a channel 7 through the tongue 1, between the apertures B, which will receive the projection 5 of the next layer of blocks. These corner blocks are not mortised their entire length, as in the other blocks, but are only 55 cut away enough so that the block will fit over the tongues of the two blocks and its outer surface will be flush with the surfaces of the other blocks, and not leave an opening or break in the outer surface. These 60 corner blocks are made right and left, so that the projections or recesses always correspond.

From the foregoing it will be seen that I have provided a block which is cheap to 65 manufacture, and which at the same time does away with the half or miter blocks, and which will prevent the rain or wind from blowing or sifting through the walls.

It is evident that many slight changes 70 might be made in the form and arrangement of the several parts described without departing from the spirit and scope of my invention, and hence I do not wish to limit myself to the exact construction herein set 75 forth, but:—

Having fully described my invention, what I claim as new and desire to secure by Letters Patent, is:—

A hollow building block of rectangular 80 form having two orifices extending therethrough from top to bottom only, the block having a depression or mortise at one of the terminals of the orifices, and a tenon at the opposite terminal of the orifices surrounding 85 the same, whereby the block is made to fit corresponding parts in adjacent blocks placed above and below, each block also provided with a vertically disposed mortise and tenon extending from top to bottom in the 90 solid part of the block and unbroken by orifices and adapted to fit the corresponding parts of the next adjacent blocks in a tier.

In testimony whereof I have signed my 95 name to this specification in the presence of two subscribing witnesses.

JAMES M. AULT.
